UNITED STATES PATENT OFFICE.

ANTHONY M. ROBESON, OF JOHANNESBURG, TRANSVAAL, AND CLAUDE A. BETTINGTON, OF BOSTON, MASSACHUSETTS.

PROCESS OF BURNING FUEL AND OTHER MATERIALS.

No. 817,990.

Specification of Letters Patent.

Patented April 17, 1906.

Application filed April 13, 1905. Serial No. 255,471.

To all whom it may concern:

Be it known that we, ANTHONY M. ROBESON, residing at Johannesburg, Transvaal, South Africa, and CLAUDE A. BETTINGTON, residing at Boston, in the county of Suffolk, State of Massachusetts, have invented certain new and useful Improvements in Processes of Burning Fuel and other Materials, of which the following is a full, clear, and exact description, such as will enable others skilled in the art to which it appertains to make and use the same.

Our invention relates to improvements in processes for burning different substances or materials.

One of the objects of the invention is to improve on the prior processes for burning material, and especially coal in the form of finely-divided particles or dust, so as to get the greatest efficiency.

Other objects will appear from the herein-after description.

It is a well-known fact that when coal is reduced to a fine powder and introduced into a furnace with the correct amount of air the combustion of the coal is practically perfect, provided that the coal-supply, the quality thereof, and the air supplied thereto remain constant within narrow limits; but when any of these factors change either the fire goes out or it burns very inefficiently.

After many experiments and from practical demonstrations we have discovered that if in burning finely-divided or pulverized coal introduced into a furnace in a stream mixed with air the products of combustion and the burning fuel be turned back upon themselves and returned alongside of or in proximity to the incoming stream or split and returned along two sides of the furnace or spread out in a circular or mushroom form and returned on all sides a regenerative action is secured, more of the fuel is consumed, and a greater efficiency is obtained from the material burned than heretofore. The act of changing direction of flow of the unconsumed fuel projected into the furnace and the gases or products of combustion causes eddy-currents, which decreases the velocity of the flow of the fuel and the products of combustion in the furnace and stirs up the particles so as to produce a more rapid chemical reaction, whereby the material is

more quickly burned and a greater heat is obtained. We have also discovered that the best results are obtained by mixing the air or other combustion-supporting gas with the fuel before supplying the fuel to the furnace and forcing the mixture in the furnace in an upward direction and causing the products of combustion and the ignited fuel to fall down and double back on themselves alongside or through the incoming mixture of the fuel and air in a downward direction.

Broadly speaking, our invention consists in burning the material causing the products of combustion and the ignited material to double back on themselves. Although good results may be obtained by forcing the material in a horizontal direction or in a downward direction in the furnace so long as the products of combustion and burned material are caused to double back upon themselves, yet we have found that the best results are obtained by forcing the material in an upward direction in the furnace. While various apparatus may be used for carrying out our process, the furnace which we will now describe is the one which we have found to work admirably and the one which we prefer to use. The said furnace is illustrated in the accompanying drawings, which form a part of this application, and in which the same reference characters refer to the same parts in the different views.

Figure 1 of the drawings is a cross-section of the furnace together with the boiler which is heated by the combustion of the material in the furnace. Fig. 2 is a cross-section on the line 1 1 of Fig. 1.

The part marked A is the outer wall of the furnace.

B is a retort having a slag-pit immediately below it, this retort at the top being preferably curved or dome-shaped, as shown.

D is a pipe through which the fuel, which may be finely divided or pulverized coal mixed with air or other combustion-supporting gas, is supplied to the retort. The inner end of this pipe is curved upwardly, as shown at D', and extends upwardly into the retort, so that the fuel may be supplied in an upward direction. The fuel after being mixed with the air is forced through this pipe, so that it will enter the retort in a stream. While we have stated that the air is prefer-

ably mixed with the fuel before it is forced through the pipe D, yet in some cases it may be mixed with the fuel just as the fuel leaves the upper end D' of the pipe. The end of the 5 supply-pipe where it projects within the retort may be either protected by refractory covering E or water-jacketed.

The furnace or retort should have its walls F formed of as refractory material as possible 10 owing to the intense heat produced within it and should be made so as to permit of free expansion, especially in a vertical direction. In the construction shown it is surrounded on three sides by the walls of the boiler-setting, 15 which are preferably kept a short distance away from the retort, so as to provide an air-space to lessen the heat radiation. At the bottom of the retort on one side is an outlet G for the escape of the products of combustion. 20 The height of the retort may be such as to insure a complete combustion of all the particles of fuel. On the side of the retort opposite the outlet G is an opening H, which is made use of for igniting the fuel and as an inspection-door. This opening is covered by a 25 vertically-sliding door. This opening may be entirely dispensed with when using certain kinds of coal or for certain services; but this would in no way affect the operation of 30 the invention. The bottom of the retort is shown open throughout its whole section and opens into the slag-pit C. This construction is only necessary, however, when fuel of a slag-forming nature is burned. J is the 35 boiler, and K is the outlet to permit the products of combustion to escape after passing through the boiler.

In starting the furnace a brazier filled with wood and greasy waste is introduced 40 through the opening H and lighted. The blast is then started at a very low rate, and the powdered fuel is forced through the pipe D and discharged through the vertical end D' thereof at such a rate as not to smother 45 the fire in the brazier. This powdered fuel partially ignites and gradually heats up the retort. In a short time the retort is sufficiently hot to allow the removal of the brazier, after which the rate of combustion can 50 be increased until working conditions are reached. During the burning of the fuel it is forced upwardly, and the products of combustion and that part of the fuel which has not been entirely consumed are caused to 55 double back upon themselves and act in a regenerative way to increase the heat of the burning incoming fuel.

While we have described this furnace as using a finely-divided coal, we do not intend 60 to limit our process to the burning of such fuel, as it is clear that our process may be carried out successfully by using other solid fuels—for example, powdered coke-dust or any other solid material—and it may also be 65 carried out by the use of liquid fluids, such as

crude or any other kind of oil, which may be forced through the supply-pipe D D' and permit it to escape into the retort in a spray or fine divided particles. Our process may also be used in the treatment of fuel ores and fluxes, which are preferably ground together in any suitable fine-grinding machine and mixed with air.

It might be well to state that it is preferable to cause the draft of the furnace to be so 75 regulated as to make the pressure within the furnace about equal to that of the atmosphere to avoid loss of heat through infiltration of air; but if for any reason it be desirable to have the pressure within the furnace 80 greater or less than that of the air the process will work equally well.

As many changes could be made in the above construction and many apparently widely different embodiments of our invention could be made without departing from the scope thereof, we intend that all matter contained in the above description or shown in the accompanying drawings shall be interpreted as illustrative and not in a limiting 85 sense. We desire it also to be understood that the language used in the following claims is intended to cover all of the generic and specific features of the invention herein described and all statements of the scope of 90 the invention, which, as a matter of language, might be said to fall therebetween.

Having described our invention, what we claim as new, and desire to secure by Letters Patent, is—

1. The process of combustion which consists in injecting a fuel into a combustion-chamber, igniting the same, and causing the products of combustion and any unconsumed particles thereof to double back and envelop 105 the incoming fuel.

2. The process of combustion which consists in feeding a solid, pulverulent or less finely divided fuel into a combustion-chamber, igniting the fuel, causing the products of 110 combustion and unconsumed particles of the fuel to double back and to envelop the fuel being supplied to the chamber.

3. The process of combustion which consists in mixing with a fuel a supporter of combustion, feeding the mixture into a combustion-chamber, igniting the fuel, causing the products of combustion and the unconsumed particles to double back and to envelop the 115 incoming fuel.

4. The process of combustion which consists in injecting a solid, pulverulent or less finely divided fuel and a supporter of combustion into a combustion-chamber, igniting the fuel, causing the products of combustion and the unconsumed particles of the fuel to double back and to envelop the incoming fuel.

5. The process of combustion which consists in projecting a substance and a supporter of combustion into a combustion-chamber,

igniting the substance, and causing the products of combustion and unconsumed particles to double back and envelop the burning substance.

5. The process of combustion which consists in injecting a solid, pulverulent or less finely divided fuel and a supporter of combustion into a combustion-chamber having an outlet for the escape of the products of 10 combustion adjacent to the point where the fuel is injected into the combustion-chamber, igniting the fuel, causing the products of combustion and the unconsumed particles of the fuel to double back and to envelop the incoming fuel, the products of combustion passing through said outlet.

15. The process of combustion which consists in injecting a finely-divided material and a supporter of combustion into a combustion-chamber in one direction, igniting the material, causing the products of combustion and the unconsumed particles of said material to return in the opposite direction adjacent to and enveloping the incoming material, whereby a regenerative action is 20 secured.

25. The process of combustion which consists in injecting a substance and a supporter of combustion into a combustion-chamber substantially vertically in one direction, igniting the substance, causing the products of combustion and the unconsumed particles of said substance to return in the opposite direction to the incoming substance, and permitting the said particles and products of combustion to pass on from said combustion-chamber.

30. The process of combustion which consists in projecting a combustible material and a supporter of combustion upwardly into a combustion-chamber, igniting the same and causing the burning material to be in motion or in suspense without separation from the supporter of combustion until combustion is complete.

45. The process of combustion which consists in injecting pulverulent or less finely divided fuel and a supporter of combustion upwardly into a combustion-chamber, igniting the fuel, maintaining the burning fuel in motion or suspense without separating the fuel from the supporter of combustion, until combustion is complete.

50. The process of combustion which consists in injecting a finely divided or pulverulent substance into a combustion-chamber in an upward direction, supplying to the substance a supporter of combustion, igniting the substance, causing the products of combustion and the unconsumed portions of said substance to return downwardly in proximity to the incoming substance and to envelop the same.

55. The process of combustion which consists in injecting a solid fuel in a finely-di-

vided or pulverulent state into a combustion-chamber in a substantially vertical direction, supplying to the fuel a supporter of combustion, igniting the fuel, causing the unconsumed portions of the fuel and the products of combustion to return adjacent to the incoming fuel, and permitting the products of combustion and unconsumed particles to escape from the combustion-chamber.

60. The process of combustion which consists in injecting a solid fuel in a finely-divided state into a combustion-chamber in an upwardly direction, supplying to the fuel a supporter of combustion, igniting the fuel, causing the burning fuel and the products of combustion to spread out in mushroom form and to return downwardly in proximity to the incoming fuel, and permitting the products of combustion to pass on.

65. The process of combustion which consists in injecting a substance and a supporter of combustion into a combustion-chamber, igniting the substance, causing the burning substance and the products of combustion to double back and return alongside of the incoming substance, whereby eddy-currents are set up, as and for the purpose set forth.

70. The process of combustion which consists in mixing a substance and a supporter of combustion, injecting the mixture into a combustion-chamber, igniting the substance, causing the burning mixture and products of combustion to double back and return alongside of the path of the mixture injected, by which the burning material and products of combustion are under the retarding influence of the injected material.

75. The process of combustion which consists in injecting a finely-divided solid fuel and a supporter of combustion into a combustion-chamber, igniting the fuel, causing the products of combustion and the burning fuel to double back and be in suspense while burning.

80. The process of combustion which consists in injecting a substance and a supporter of combustion into a combustion-chamber opened for the passage of the products of combustion and unconsumed particles of said substance, igniting said substance, causing said substance and the products of combustion to double back on themselves in proximity to the incoming substance and to envelop the same, by which the burning substance and products of combustion are under the retarding influence of the incoming substance and a regenerative action is obtained, and permitting the products of combustion to pass on.

85. The process of combustion which consists in injecting a finely-divided solid fuel in an upwardly direction into a combustion-chamber having an opening for the passage of the products of combustion, supplying a

- supporter of combustion to the fuel, igniting the fuel, causing the ignited fuel and the products of combustion to double back upon themselves in a downward direction in proximity to and enveloping the upwardly-moving fuel, by which the downward movement of the burning fuel and products of combustion is retarded and a regenerative action is obtained, and permitting the unconsumed products to pass on.
19. The process of combustion which consists in injecting a finely-divided solid fuel and a supporter of combustion upwardly into a combustion-chamber open only at the lower part thereof, causing the products of combustion and the unconsumed particles of the fuel to double back and move downwardly, and permitting the products of combustion and unconsumed material to pass on from the combustion-chamber.
20. The process of combustion which consists in mixing a substance and a supporter of combustion, forcing said mixture into a combustion-chamber having an opening for the escape of the products of combustion, igniting said substance, causing the ignited substance to double back on the incoming substance, keeping the substance in suspense until combustion is complete, and permitting the products of combustion to pass on.
21. The process of combustion which consists in mixing with pulverulent substances a supporter of combustion, injecting said substances into a combustion-chamber having an opening for the passage of the products of combustion, igniting said substances, causing the ignited substances to double back upon the incoming substances, causing the burning substances to be supported by the incoming substances while burning, and permitting the products of combustion to pass on.
22. The process of combustion, which consists in injecting a substance in an upward direction into a combustion-chamber having an opening therein for the passage of the products of combustion, igniting said substance, keeping the substance in suspense while burning, and permitting the products of combustion to pass on.
23. The process of combustion which consists in mixing with a substance a supporter of combustion, injecting the mixture upwardly into a combustion-chamber having an opening for the passage of the products of combustion, igniting said substance, causing the ignited substance to double back on the incoming substance and against the retarding influence thereof, and permitting the products of combustion to pass on.
24. The process of combustion which consists in injecting a pulverulent substance upwardly into a combustion-chamber having an opening for the passage of the products of combustion, igniting said substance, causing the ignited substance to double back on the incoming substances, permitting the unconsumed substance under the retarding influence thereof, whereby part of the burning substance is held in suspense, and permitting the products of combustion to pass on.
25. The process of combustion which consists in mixing with a pulverulent substance a supporter of combustion, injecting the said mixture upwardly into a combustion-chamber having an opening for the passage of the products of combustion, igniting said substance, causing the ignited substance to double back on the incoming substance, keeping some of the burning substance in suspense while burning, and permitting the products of combustion and unconsumed material to pass on.
26. The process of combustion which consists in injecting a pulverulent substance and a supporter of combustion substantially vertically into a combustion-chamber, said chamber being open, near the incoming material, for the escape of the products of combustion, igniting the substance and causing the products of combustion and burning substance to double back on the incoming substance, and permitting the products of combustion and the unconsumed material to pass on.
27. The process of treating pulverulent substances, which consists in injecting said substances and a supporter of combustion into a combustion-chamber having openings therein, igniting the combustible substances, causing the products of combustion and the substances to double back on the incoming substances so that the said incoming substances will exert a retarding influence on the returning products of combustion and substances, permitting the products of combustion to pass on in one direction, and the unconsumed material to fall in another direction.
28. The process of treating a pulverulent substance, which consists in injecting said substance and a supporter of combustion upwardly into a combustion-chamber, having openings therein, igniting said substance, causing the products of combustion and the ignited substance to double back on the incoming substance, so that the said incoming substance will exert a retarding influence on the returning products of combustion and keep the same in suspense while burning, permitting the products of combustion to pass on in one direction, and some of the unconsumed substance to pass in another direction.
29. The process of treating pulverulent substances, which consists in injecting said substances in an upward direction into a combustion-chamber having an opening at or near the bottom thereof, igniting said substances, causing said ignited substances and products of combustion to double back on the incoming substances, permitting unconsumed

sumed products and products of combustion to pass on in a downward direction.

30. The process of treating pulverulent substances, which consists in injecting said substances and a supporter of combustion upwardly into a combustion-chamber, igniting said substances, causing said ignited substances and products of combustion to double back on the incoming substances, permitting the unconsumed material and products of combustion to pass from the combustion-chamber in a downward direction.

31. The process set forth which consists in mixing together pulverulent substances one of which is combustible, injecting said substances into a combustion-chamber, igniting the combustible substance, causing the ignited substance and the products of combustion to double back on themselves, whereby the motion of the ignited substances and products of combustion is retarded and some of the burning substances are held in suspense until combustion is complete, and permitting the unconsumed material and the products of combustion to pass from the combustion-chamber.

32. The process set forth which consists in injecting pulverulent substances, at least one of which is combustible, upwardly into a combustion-chamber, igniting the combustible material, causing said ignited material and the products of combustion to double back on themselves, whereby the return movement of the ignited material and products of combustion is retarded and some of the burning material is held in suspense while burning, permitting the unconsumed material and products of combustion to pass from the

combustion-chamber in a downward direction.

33. The process of combustion which consists in injecting a pulverulent substance and a supporter of combustion into a combustion-chamber, igniting the substance, permitting the products of combustion to pass from the combustion-chamber in such a manner as to be under the retarding influence of the incoming material and the heavier particles of the burning material are prevented from separating from the lighter while the material is burning.

34. The process of combustion which consists in injecting a pulverulent or less finely divided substance and a supporter of combustion into a combustion-chamber, igniting the substance, permitting the products of combustion to pass from said combustion-chamber in such a manner as to be under the retarding influence of the incoming substance and the heavier particles prevented from being separated by gravity while burning.
